Des. 218,934
Patented Oct. 13, 1970

218,934

FLUID FLOW SENSOR

Rene Cordero, Attleboro, and Roy V. Jones, Plainville, Mass., assignors to Texas Instruments Incorporated, Dallas, Tex., a corporation of Delaware

Filed Mar. 10, 1969, Ser. No. 16,141

Term of patent 14 years

Int. Cl. D13—03

U.S. Cl. D26—13

Fig. 1.

Fig. 2.

Fig. 3.

FIG. 1 is a side view of our new design for a fluid flow sensor.

FIG. 2 is a left end view of the sensor shown in FIG. 1.

FIG. 3 is a right end view of the sensor shown in FIG. 1.

The undisclosed side of the sensor is a mirror image of the side shown.

The broken lines are for illustrative purposes only.

We claim:

The ornamental design for a fluid flow sensor, substantially as shown and described.
